United States Patent

Des. 237,332
Patented Oct. 28, 1975

237,332

ARM CHAIR OR THE LIKE

Harry Laylon, Syracuse, N.Y., assignor to Dart
Industries Inc., Los Angeles, Calif.

Filed Jan. 7, 1974, Ser. No. 431,448

Term of patent 14 years

Int. Cl. D6—01

U.S. Cl. D6—69

FIG. 1 is a perspective front view of an arm chair embodying my ornamental design;

FIG. 2 is a perspective back view thereof; and

FIG. 3 is a cross-sectional view of the leg portion thereof taken along line 3—3 of FIG. 1.

I claim:

The ornamental design for an arm chair or the like, substantially as is shown.
